(57) **CLAIM**

The ornamental design for a base unit with a headset, as shown and described.

DESCRIPTION

FIG. 1 is a top perspective view of a base unit with a headset showing my new design;

FIG. 2 is a front plan view thereof;

FIG. 3 is a rear plan view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective view of the base unit shown separately for purposes of illustration;

FIG. 9 is a front view thereof;

FIG. 10 is a rear view thereof;

FIG. 11 is a right side view thereof;

FIG. 12 is a left side view thereof;

FIG. 13 is a top plan view thereof;

FIG. 14 is a bottom plan view thereof;

FIG. 15 is a top perspective view of the headset shown separately for purposes of illustration;

FIG. 16 is a front view thereof;

FIG. 17 is a rear view thereof;

FIG. 18 is a bottom plan view thereof;

FIG. 19 is a top plan view thereof;

FIG. 20 is a front end view thereof; and,

FIG. 21 is a rear end view thereof.
